(57) **CLAIM**

The ornamental design for a safety ladder as shown and described.

DESCRIPTION

FIG. 1 is a perspective view of a first embodiment of a safety ladder showing the new design.

FIG. 2 is a front view of the safety ladder of FIG. 1.

FIG. 3 is a rear view of the safety ladder of FIG. 1.

FIG. 4 is a first side view of the safety ladder of FIG. 1.

FIG. 5 is a second side view of the safety ladder of FIG. 1.

FIG. 6 is an enlarged top view of the safety ladder of FIG. 1.

FIG. 7 is an enlarged bottom view of the safety ladder of FIG. 1.

FIG. 8 is a perspective view of a second embodiment of a safety ladder.

FIG. 9 is a front view of the embodiment of FIG. 8.

FIG. 10 is a rear view of the embodiment of FIG. 8.

FIG. 11 is a first side view of the embodiment of FIG. 8.

FIG. 12 is a second side view of the embodiment of FIG. 8.

FIG. 13 is an enlarged top view of the safety ladder of FIG. 8; and,

FIG. 14 is an enlarged bottom view of FIG. 8.

The broken lines are for the purpose of illustrating portions of the safety ladder that form no part of the claimed design.
